GAS LIGHTER

Filed Oct. 6, 1928

UNITED STATES PATENT OFFICE

HOMER W. JONES, OF NEWARK, NEW JERSEY, ASSIGNOR TO OXWELD ACETYLENE COMPANY, A CORPORATION OF WEST VIRGINIA

GAS LIGHTER

Application filed October 6, 1928. Serial No. 310,880.

This invention pertains to gas lighters and more specifically to an improved and simplified construction thereof.

Gas lighters known heretofore have been unnecessarily complicated in construction, costly to manufacture, difficult to assemble, and unreliable in operation. Therefore, the object of this invention is the provision of a gas lighter that is simple in construction, easy to assemble, low in cost, and reliable in operation. Furthermore, my invention also includes all of the other objects and novel features hereinafter described and shown.

I attain the objects of this invention by the mechanism shown in the accompanying drawing, in which:

Figure 1 is a front elevation of my improved gas lighter;

Figure 2 is a side elevation of the same;

Figure 3 is a plan or top view of the same;

Figure 4 is a transverse section along the line 4—4 of Figure 1 looking in the direction of the arrows; and

Figures 5 and 6 are front elevations of alternative gas lighter operating keys.

The gas lighter shown in the drawing and embodying this invention is composed of a frame 10 having an integral backwardly extending clamp adapted for attachment to a gas burner and comprising arms 11 and 12 that are formed to fit the cylindrical body of a gas burner to which they may be clamped by the bolt 13 passing through the free ends of the arms 11 and 12.

The top of the frame 10 is bent forward forming a bracket 14 and about midway of the frame 10 a tongue is cut out and bent forward forming a bracket 15 similar to the bracket 14. Each of the brackets 14 and 15 have an aperture therethrough near the outer end that forms a bearing for a shaft 16 that passes through the brackets 14 and 15 in which the shaft 16 is adapted to rotate.

Firmly pressed upon and riveted to the upper end of the shaft 16 that protrudes through and extends upwardly from the bracket 14 is a friction wheel 17 of hardened steel. This wheel 17 may be made of two or more disks or it may be a single piece of metal, and the periphery may be simply

roughened although, preferably, it has a large number of fine teeth cut therein. Furthermore, the friction wheel may be of hardened and tempered high carbon steel or of case hardened low carbon steel as either material is satisfactory.

Formed integral with the shaft 16 and positioned so it lies just below the under side of the bracket 15 is a toothed wheel 18. Preferably, this wheel is formed with four teeth each having a face that rises more abruptly than the back. Of course, the wheel 18 may be made separately and pressed on the shaft 16 and the number of teeth may be either increased or decreased to vary the operating characteristics of the gas lighter.

Formed integral with the bracket 14 is a hollow cylindrical holder 19 that supports a cylindrical piece of pyrophoric metal 20 opposite the face of the friction wheel 17. Formed integral with the side of the frame 10 are two ears 21 and 22. Each of these ears is bent around and formed to a waved portion 23' of a spring 23 thereby securing it to the frame 10 of the gas lighter so it will neither twist nor slide in the clamping ears. The spring 23 is formed from a single piece of metal spring wire that is bent so one end of the wire is clamped by and held in the overturned ear 22 from which it extends to approximately the center of the frame 10 in back of the toothed wheel 18 where it makes a right angle turn and extends a short distance upward and then turns and extends back along a parallel course to the other overturned clamping ear 21 thereby forming a closed loop 24. From the other side of the overturned ear 21 the wire continues twice around a helical coil 25 and then upward to the holder 19 where the free end 26 presses against the outer end of the pyrophoric metal 20 and holds it firmly against the face of the friction wheel 17. A slot 27 in the under side of the holder 19 permits the end 26 of the spring 23 to follow the pyrophoric metal 20 almost to the face of the friction wheel 17 as the pyrophoric metal 20 is worn away and shortened by the abrading action of the friction wheel 17 during the operation of the gas lighter.

The shaft 16 has a portion 27' extending downward below the lower face of the toothed wheel 18 with a transverse aperture 28 diametrically therethrough which holds the gas lighter operating key 29. This key is preferably made of a single piece of metal wire such as brass, bronze or steel that has an elastic quality and is bent so the upper end is formed into a hook 30 that hangs loosely in the aperture 28 and the lower end is formed into a grip 31 adapted for being grasped by a person operating the gas lighter. The central portion 32 of the key 29, between the hook 30 and the grip 31, is flattened so it is elastic or resilient and is adapted to bend, give, deform, or be torsionally deflected when the gas lighter is operated. The key 29 may be made in different forms from that shown in Figures 1 and 2. For instance, the elastic portion 32 may be twisted so it is in the form of a spiral 33 as shown in Figure 5, or the central portion of the key may be made elastic by bending the wire into the form of a helix 34 as shown in Figure 6. Furthermore, the portion of the key 29 forming the grip 31 may be a different shape from that shown or it may be made from a separate piece of metal and attached to the key.

The teeth in the toothed wheel 18 are cut so that when the gas lighter is operated the toothed wheel 18 rotates backward like a ratched wheel, and the friction wheel 17 is assembled on the shaft 16 so that when the gas lighter is operated the friction wheel rotates forward like a milling cutter.

If it were not for the retarding action of the spring 23 against the toothed wheel 18 and the elastic portion 32 of the operating key 29, the friction wheel 17 would be rotated at the speed of the key 29 during the operation of the gas lighter. But igniters constructed to operate in this manner are unsatisfactory because it is difficult for an operator to rotate the friction wheel fast enough to cause it to throw an adequate shower of sparks. Therefore, the retarding mechanism and the elastic key are incorporated with the gas lighter so the friction wheel 17 is intermittently retarded and rotates slower than the grip 31 of the key 29 during a portion of the operating movement and faster during another portion thereby throwing intermittent showers of sparks in adequate quantities.

When at rest the position of the rotating parts of the gas lighter is usually with the back side of one of the teeth, such as 36, of the wheel 18 in contact with the vertical portion 35 of the spring loop 24. The gas lighter is operated by grasping the grip 31 of the key 29 and giving it a partial turn or revolution and, viewed from above, the direction of rotation is counter-clockwise. When the toothed wheel 18 is made with four teeth as shown in the drawing the partial

turn or revolution necessary to operate the gas lighter is a quarter turn, but by varying the number of teeth on the wheel 18 the operating movement may be made longer or shorter at will. For instance, with three teeth on the wheel 18 the operating movement will be one third of a revolution, and with five teeth on the wheel 18 the operating movement will be one fifth of a revolution.

During the early portion of the operating movement the rotating parts of the gas lighter above the elastic portion 32 of the key 29 are retarded by the force of the vertical portion 35 of the spring loop 24 against the back of the tooth 36, so the elastic portion 32 of the key 29 bends or is torsionally deflected thereby permitting the rotating parts of the gas lighter above the elastic portion 32 to lag behind the grip 31 of the key 29 below the elastic portion. When the central elastic portion 32 of the key 29 has been torsionally deflected or bent to the point where the rotative pressure exerted by it on the rotating parts of the gas lighter is sufficient to overcome the retarding effect of the spring loop 24 on the toothed wheel 18, the tooth 36 forces the spring loop 24 back and passes under it, thereby freeing the rotating parts of the gas lighter from the retarding effect of the spring loop 24 and permitting the torsionally deflected elastic portion 32 of the key 29 to straighten and rapidly rotate the rotating parts of the gas lighter above the elastic portion 32 for about a quarter of a revolution thereby throwing a shower of

sparks from the pyrophoric metal 20 adequate to ignite escaping gas. After the operating movement the rotating parts of the gas lighter come to rest with the back of the next tooth against the vertical portion 35 of the spring loop 24 from which position they may be forced through another operating movement by a quarter turn of the key 29.

The spring 23 is made so it exerts a much greater pressure on the toothed wheel 18 than it does on the pyrophoric metal 20 by being attached to the frame 10 so the vertical portion 35 of the loop 24 exerts a pressure on the toothed wheel 18 of the elastic force of two strands of the spring wire and a pressure on the pyrophoric metal 20 of the elastic force of one strand of the spring wire. By this ingenious construction the spring 23 is made from a single piece of spring wire so it takes the place of two springs having widely different tensions.

The toothed wheel may be made with teeth of a different shape from those shown in the drawing. For instance, the retarding effect of the spring loop 24 may be increased by steepening the slope of the back side of the teeth and, conversely, the retarding effect may be decreased by making the slope or rise more gradual. With the teeth of the wheel 18 formed as shown in the drawing, the

face of the teeth are so steep that the rotating parts of the gas lighter cannot be rotated in a reverse direction. Also, when the vertical portion 35 of the spring loop 24 falls from the top of a tooth such as 36 and rides down its face, it tends to rapidly accelerate its rotation through a relatively small arc. By altering the angle of the face of the teeth the rapidity of acceleration and the length of the arc through which the wheel is accelerated may be varied. For instance, by making the drop down the face of the teeth less abrupt, the length of the period of acceleration may be increased and the speed of acceleration may be decreased. Furthermore, the acceleration may also be controlled by moving the spring supports 21 and 22 either nearer to or farther from the center of the toothed wheel 18.

Various other changes may be made in the construction and arrangement of the component parts of the gas lighter shown and described herein without departing from the spirit of the invention or sacrificing any of the rights thereunder.

I claim:

1. In a gas lighter, a friction wheel, a toothed wheel connected to said friction wheel, means for holding a piece of pyrophoric metal opposite the face of said friction wheel, means for rotating said friction wheel and said toothed wheel, and a spring having one portion that presses said pyrophoric metal against said friction wheel and another portion that presses against the periphery of said toothed wheel.

2. In a gas lighter, a friction wheel, a toothed wheel connected to said friction wheel, means for holding a piece of pyrophoric metal opposite the face of said friction wheel, means for rotating said friction wheel and said toothed wheel, and a spring formed from a single piece of wire so it presses said pyrophoric metal against said friction wheel with the elastic force of one strand of said wire and so it presses against said toothed wheel with the elastic force of two strands of said wire.

3. In a gas lighter, a frame adapted for attachment to a gas burner, a shaft carried by said frame, a friction wheel carried by said shaft, a toothed wheel carried by said shaft, a piece of pyrophoric metal held opposite the face of said friction wheel, means for manually rotating said shaft, and a spring having one end and a central portion thereof attached to said frame and formed so it has a flexible end that presses said pyrophoric metal against said friction wheel and a flexible loop that bears against said toothed wheel to intermittently retard the rotation of said friction wheel.

4. In a gas lighter, the combination of a frame adapted for attachment to a gas burner; a friction wheel; a shaft carrying

said friction wheel; a toothed wheel carried by said shaft; means for holding a piece of pyrophoric metal opposite the face of said friction wheel; a key operative to rotate said shaft; and a spring carried by said frame so one portion thereof presses said pyrophoric metal against said friction wheel and another portion thereof retards the rotation of said shaft.

5. In a gas lighter, the combination of a frame adapted for attachment to a gas burner; a shaft carried by said frame; a friction wheel carried by said shaft; a toothed wheel carried by said shaft; means for holding a piece of pyrophoric metal opposite the face of said friction wheel; resilient means for rotating said shaft; and unitary means for pressing said pyrophoric metal against said friction wheel and for exerting pressure on the periphery of said toothed wheel to intermittently retard the rotation of said friction wheel.

In testimony whereof, I affix my signature.
